UNITED STATES PATENT OFFICE

JAMES H. WILY, OF BETHLEHEM, PENNSYLVANIA

TOP

Application filed May 14, 1930. Serial No. 452,152.

This invention relates to improvements in tops and the principal object is the provision of such a toy which is simple in construction, easy to manufacture on a production basis, which will spin for a long period of time, which is neat and attractive in appearance, may be readily and artistically decorated and which has provision for storing the cord for spinning the top.

10 A further object of this invention is a toy of this character in which the rotating body is composed of cast metal provided with a decoration receiving recess on its top and a cord receiving recess on its bottom, the last 15 recess being adapted to be closed by a disk upon which may be placed decorations or advertising, this disk serving to hold the cord in place.

To the accomplishment of the foregoing and 20 such other objects as may hereinafter appear, this invention consists in the construction, combination and arrangement of parts hereinafter described and then sought to be defined in the appended claims, reference being had to the accompanying drawing forming a part hereof and which shows, merely for the purpose of illustrative disclosure, a preferred embodiment of my invention, it being expressly understood, however, that various changes may be made in practice within the scope of the claims without digressing 25 from my inventive idea.

In the drawing—

30 Figure 1 represents a perspective view of a top embodying my invention.

Figure 2 is a top plan view of the same.

Figure 3 is a bottom plan view of the same; and

40 Figure 4 is a vertical longitudinal cross section throughout the top completely assembled for display and shipment.

In the drawing the numeral 1 designates the body of the top, 2 the handle and 3 the 45 spindle or stem. This spindle or stem is provided with the pointed headed end 4 which forms the spinning point. The spindle or stem 3 is driven into the handle 2 through an elongated opening or bore 5 which is formed in the elongated depending

extension 6 of the body of the top. This extension 6 is preferably tapered downwardly and forms the member upon which the cord is wrapped so that when pulled the body 1 as a whole is rotated on the spindle or 55 stem 3.

This body is preferably formed of cast iron or other suitable material being of considerable weight and having a portion formed of disk shape or conformation as at 7 so that when the body is rotated the actuating force 60 will maintain the top upright.

The top surface of the body 1 is provided with a recess which is adapted to receive a decorative or ornamental disk 9 which may 65 be secured therein by any suitable means. A very effective method is by applying the disk in position when the lacquer coloring material on the top body is still moist, this lacquer serving effectively as an adhesive. 70

On the underside of the body 1 provide another recess 10 which is of substantial depth and is adapted to receive the coiled string or cord 11 which is used for spinning the top. This string or cord is held in place 75 by means of a disk 12 which may be made of paper, celluloid or other suitable composition and is frictionally held in place by engaging the tapered extension 6 of the body.

It is to be noted that by providing the two 80 recesses 8 on the top and 10 on the bottom the intermediate portion of the body is much less in thickness than the outside edge or periphery of the same. In other words, the outer portion of the disk part 7 of the body 85 is thicker and heavier than the intermediate part thereof which increases the actuating force when spinning, and increases the length of time that the top will spin.

If desired the top of the body may be provided with the boss or projection 13 to provide centering means for the decorative element 9 and also to provide a spacing means to space the body 1 as a whole between the handle 2 and the head or tip 4. 90

95 What I claim is:

1. A top including, in combination, a handle, an elongated spindle secured thereto and having a spinning tip or head, a heavy body 100 rotatably mounted with respect to said spin-

dle and said handle and having an elongated extension provided with a bore to receive said spindle whereby the body has an extended bearing on said spindle, said body having its outer edge thickened so as to increase the actuating force when the body rotates, said body being provided with a depression on its underside, a string or cord coiled about the extension of said body within said depression, and a removable disk frictionally engaging said extension and substantially closing said depression so as to hold said cord or string in position.

2. A top, including, in combination, a handle, an elongated spindle secured thereto and having a spinning top or head, a body member rotatably mounted on said spindle and having an elongated extension provided with a bore to receive said spindle whereby the body has an extended bearing on said spindle, said body member being provided with a depression in its under side, and a removable apertured disk frictionally engaging said extension adjacent said depression, said disk being of substantially the same size as said depression and being adapted to hold a string or cord in position in said depression.

In testimony that I claim the foregoing, I have hereunto set my hand this 9th day of May, 1930.

JAMES H. WILY.
